Des. 241,501
Patented Sept. 21, 1976

241,501

FASTENER DRIVING TOOL

Richard H. Doyle, Mount Prospect, Salvatore L. Morabito,
Northlake, and Andrew I. Yohana, Des Plaines, Ill.,
assignors to Duo-Fast Corporation

Filed June 5, 1975, Ser. No. 583,958

Term of patent 14 years

Int. Cl. D8—05

U.S. Cl. D8—49

Fig. 1

Fig. 2

Fig. 3

Fig. 4

Fig. 5

Fig. 5

FIG. 1 is a side view of a fastener driving tool embodying our new design;

FIG. 2 is a top view of the tool;

FIG. 3 is a bottom view of the tool;

FIG. 4 is a side view of the tool showing the side opposite to that shown in FIG. 1;

FIG. 5 is a front view of the tool; and

FIG. 6 is a rear view of the tool.

We claim:

The ornamental design for a fastener driving tool, substantially as shown and described.
